UNITED STATES PATENT OFFICE.

CHARLES H. HODGKINS AND WALTER C. GOODWIN, OF PITTSBURGH, PENNSYLVANIA,
ASSIGNORS TO WESTINGHOUSE ELECTRIC & MANUFACTURING COMPANY, A COR-
PORATION OF PENNSYLVANIA.

ELECTROMAGNET CONTACTOR.

Application filed February 20, 1920. Serial No. 360,202.

To all whom it may concern:

Be it known that we, CHARLES H. HODGKINS, a subject of the King of Great Britain, and a resident of Pittsburgh, in the county of Allegheny and State of Pennsylvania, and WALTER C. GOODWIN, a citizen of the United States, and a resident of Pittsburgh, in the county of Allegheny and State of Pennsylvania, have invented a new and useful Improvement in Electromagnet Contactors, of which the following is a specification.

Our invention relates to electromagnets and particularly to electromagnets employed for actuating electrical contactors and similar devices.

One object of our invention is to provide a silently-operating electromagnet that is adapted for use with alternating current.

Another object of our invention is to provide an improved form of electromagnet that shall be of simple and inexpensive construction.

A further object of our invention is to provide an electromagnet having a shading coil at each juncture of relatively movable parts included in the magnetic circuit of the electromagnet.

An additional object of our invention is to provide an improved bearing for the armature of the electromagnet.

In such electromagnets as have heretofore been provided, it has been found difficult to secure uniform and proper seating of the armature members on the core members except by means of hand work. Furthermore, it has been difficult to provide a magnetic damping action at the pivotal mountings of the armatures of such electromagnets as heretofore have been provided in order to render the operation of the electromagnet silent.

According to our invention, we provide a member that may be easily machined to obtain uniform close engagement with the core member and which has limited universal movement to ensure proper seating of the armature member on the core member. Other features of our device are set forth in the specification.

Fig. 1 of the accompanying drawings is a side elevational view, partially in section on line I—I of Fig. 2, of a portion of an electromagnet contactor constructed in accordance with our invention. Fig. 2 is a top

plan view of the contactor shown in Fig. 1. Fig. 3 is a side view, partially in section on line III—III of Fig. 2 and partially in elevation, of the armature and the associated supporting member shown in Fig. 1. Fig. 4 is a top plan view, partially in section taken on line IV—IV of Fig. 3, of the armature and the armature-supporting member shown in Fig. 1.

Fig. 1 and Fig. 2 of the drawings illustrate a pair of switches, each of which comprises a stationary contact member 1 and a supporting member 2 that is mounted on a panel 3. Movable contact members 4 of the respective switches are actuated into, and out of, engagement with the co-acting stationary contact members 1 by means of an electromagnet device 5. The contactors 1 and 4 are provided with an arc shield 6, of familiar construction, which embodies a blowout coil 7 to energize magnetic side plates 8, and an arc splitter 9 that is mounted between the plates of the shield 6. A bolt 10, by means of which the contact-supporting member 2 is mounted on the panel 3, constitutes a terminal member for the blowout coil 7 and the contactor 1. A terminal bolt 11 constitutes the remaining terminal for the blowout coil 7. The plates 8, and the associated arc shield, are secured to the blowout coil by means of a bolt 12.

Each of the movable contact members 4 is pivotally mounted on a bracket 13 and is provided with a spring 14 which is compressed when the switch is closed to maintain the movable contact members in yielding engagement with the stationary contact members. The brackets 13 are mounted on opposite ends of an insulated bar 15 which is actuated by the electromagnet device 5. Energy is conducted to the movable contact members 4 by means of terminal members 16 and associated connecting leads 17.

The electromagnet actuating device 5 comprises a core member 18, a coil 19 for exciting the core member, an armature 20 that is adapted to coact with the core member 18, and an armature-supporting member 21 that is pivotally mounted on the core member and on the armature.

The core member 18 comprises similar unitary members 22 and 23 of laminated magnetic material that are clamped in opposed spaced relationship between side

plates 24 of non-magnetic material by means of bolts 25. Each of the unitary members 22 and 23 is composed of a plurality of rigidly-assembled laminæ of magnetic material. By grouping the members in opposed spaced relation, an air gap 27 is provided in the stationary portion of the magnetic circuit of the members 18.

Each of the side plates 24 is provided with laterally extending lugs 28 and 29 for rigidly mounting the core member on the panel 3 and a laterally extending lug 30 for clamping the coil 19 in place. Longitudinally-extending ears 31 constitute means for pivotally mounting the armature-supporting member 21 on the panel 3.

The coil 19 is mounted on one leg of the core member 18 and is clamped in place by means of a bolt 32. The portions 22 and 23 of the core member are each provided with a pole face 33 which coacts with the armature 20. The faces 33 are disposed in substantially coincident planes.

The armature 20 is provided with pole faces 34 which coact with faces 33 of the core member. A pivot 35 is provided for pivotally mounting the armature between depending side portions 36 of the supporting member 21.

The enlarged central portion 37 of the pivot 35 constitutes the bearing portion of the pivot for supporting the armature 20. The aperture for receiving the pivot 35 has a restricted portion 38 which engages the portion 37 of the pivot 35. The edges of the enlarged portion 37 of the pivot are sufficiently rounded to permit of a limited universal movement of the armature 20 in order that the armature may be free seating or, in other words, to permit of the best possible engagement of the coacting faces 33 and 34. Loosely fitting washers 39 position the armature between side portions 36 of the supporting member 21.

The armature 20 is pivotally mounted at its magnetic balance or in such manner that the forces of attraction of the opposite pole pieces give substantially equal and opposite turning movements about the pivotal support of the armature.

Depending side portions 36 of the member 21 constitute a pivotal mounting for the armature 20 and provide a box-like portion that partially encloses the armature. Laterally extending lugs 40 provide means for mounting the insulated bar 15 on the supporting member 21. The portions 41 of the supporting member 21 co-operate with lugs 31 of the core member 18 for pivotally mounting the supporting member on the panel 3. A tail piece 42 engages the portion 22 of the core member to limit the degree of opening of the electromagnet when coil 19 is de-energized.

By interposing the air gap 27 in the rig-

idly assembled portion of the core member 18, all chattering and noise that is incident to a structure in which the air gap is positioned between relatively movable parts, is avoided. This form of construction also enables the core member to be formed from unitary portions by assembling two such portions in opposed relation. This arrangement also greatly reduces the expense of manufacture and provides a convenient and desirable shape of punching.

A further advantage of this structure is the ease with which proper seating of the armature may be secured, even though the relatively movable parts are mechanically displaced.

After the core member 18 is rigidly assembled between side plates 24, the core member is securely clamped in a grinding machine and the pole faces 33 are ground to provide faces that are disposed in substantially coincident planes. The armature 20 is similarly constructed to provide faces 34 that will properly engage faces 33 of the core member. Since the armature is provided with a pivotal mounting which permits of a limited movement of the armature member in three directions, it is not essential that the pivotal mounting 41 be so constructed that an exact mechanical positioning of the armature results. The pivotal mounting 35 will permit of a considerable degree of adjustments between the parts. Each core-engaging face of the armature 20 is provided with a shading coil 43 for reducing the chattering of the armature member.

The relative advantage of providing an armature and a core member with co-operating faces which are so ground as to permit close engagement will be appreciated when it is pointed out, that, heretofore, it has been found necessary to file the co-operating faces of electromagnet devices, employed as this device is to be employed, in order to insure proper engagement of the faces. With the best obtainable form of hand work, uniform and close engagement of the faces cannot be secured and noise and chattering of the electromagnet results. The positioning of the air gap 27 in a stationary part of the magnetic path and the extremely close co-operation of engaging pole faces insure a magnetic path in which the reluctance is substantially constant. When the air gap of the electromagnetic device is positioned between relatively movable parts, the reluctance of the magnetic path is changed with every alteration of the relation of the parts.

By providing the armature with shading coils at each core-engaging face, a damping action is secured at each juncture of relatively movable parts which reduces chattering and other noises incident to junctures

of movable parts in the magnetic circuit that are not so arranged.

Although we have described a simple and preferred form of our invention, we desire 5 that only such limitations shall be imposed as are indicated in the appended claims.

We claim as our invention:

1. An electromagnet comprising a core member having an interposed air gap and a plurality of pole faces, and a magnetically balanced armature adapted to coact with said pole faces, said faces being positioned in substantially parallel planes.

2. An electromagnet comprising a core member having an interposed air gap and a plurality of pole faces of unlike polarity, and a pivotally mounted and magnetically balanced armature adapted to engage said faces.

3. An electromagnet comprising a core member having an interposed air gap and a plurality of pole faces of unlike polarity, and a pivotally mounted and magnetically balanced armature adapted to engage said faces, said faces being disposed in substantially coincident planes.

4. A magnetizable core member constituting a portion of a magnetic circuit, and an armature constituting an additional portion of said magnetic circuit, said armature being pivotally mounted at substantially the magnetic balance thereof.

5. A magnetizable core member having a plurality of armature-attracting portions, an armature adapted to be attracted by said portions, and a device actuated by the movement of said armature, said armature being pivotally connected to said device at a point substantially at the magnetic balance of said armature.

6. A magnetizable core member constituting a portion of a magnetic circuit, an armature constituting an additional portion of said magnetic circuit, a device actuated by said armature, and pivotal means for connecting said armature to said device at substantially the magnetic balance of said armature.

7. An electromagnet comprising a magnetizable core member having an air gap disposed in the magnetic path intermediate the extremities of said core, a pivotally mounted armature constituting a portion of the magnetic path traversing said core

member and magnetically balanced therein, 55 a device actuated by said armature, and pivotal means disposed between the extremities of said armature for pivotally connecting said armature and said core member.

8. An electromagnet comprising a magnetizable core member of U-shape having an air gap intermediate the extremities thereof, and an armature pivotally mounted and magnetically balanced in a plane disposed 65 between the legs of said core member.

9. An electromagnet embodying a core member of U-shape, an armature co-acting with the legs of said core member to complete a magnetic path, and a device actuated 70 by said armature comprising a pivotally mounted box portion having depending side portions, said armature being pivotally mounted between said side portions.

10. An electromagnet comprising a core 75 member, and an armature pivotally mounted at its magnetic balance and pivotally mounted on the core member.

11. An electromagnet comprising a core member having a plurality of armature-attracting faces, an armature coacting with said faces, a member pivotally mounted on said core member and pivotally supporting said armature at the magnetic balance of said armature.

12. The combination with an electromagnet comprising a core member having an air gap between rigid portions thereof, of a magnetically balanced armature adapted to constitute a portion of a magnetic circuit including said core member, and a shading coil associated with each portion of said magnetic circuit which traverses relatively movable parts.

13. An electromagnet comprising a magnetizable core member of U-shape having an air gap intermediate the extremities thereof, a magnetically balanced armature adapted to coact with the legs of said core member, and a plurality of shading coils disposed on said armature opposite the respective legs of said core member.

In testimony whereof, we have hereunto subscribed our names this 10 day of February, 1920.

CHARLES H. HODGKINS.
WALTER C. GOODWIN.
